UNITED STATES PATENT OFFICE

166,881

WALL SWITCH ACTUATOR

George F. Russell, Sherman Oaks, Calif., assignor to Robert Schwarz, Jr., and William H. Gottschalk, a copartnership, doing business as Falcon Plastic Products Mfg. Co., Culver City, Calif.

Application January 12, 1952, Serial No. 18,024
Term of patent 14 years

(Cl. D26—13)

To all whom it may concern:

Be it known that I, George F. Russell, a citizen of the United States of America, residing at Sherman Oaks, county of Los Angeles, State of California, have invented a new, original, and ornamental Design for a Wall Switch Actuator, of which the following is a specification, reference being had to the accompanying drawing, forming a part thereof.

Figure 1 is a front view of my wall switch actuator showing my new design.

Figure 2 is a side view thereof.

Figure 3 is a top view thereof.

Figure 4 is a back view thereof.

Figure 5 is a bottom view thereof.

I claim:

The ornamental design for a wall switch actuator, substantially as shown.

GEORGE F. RUSSELL.
